UNITED STATES PATENT OFFICE

HERMAN J. BRENDLIN, OF NEW YORK, N. Y., ASSIGNOR TO THE HAYWARD COMPANY,
OF NEW YORK, N. Y., A CORPORATION OF NEW YORK

EXCAVATING SHOVEL

Application filed September 27, 1926. Serial No. 137,934.

This invention is an improvement upon the type of shovel shown in my Patent No. 1,552,033 of September 1, 1925. In this patent the bucket is operated through a draft bridle, an adjusting bridle, a suspending bridle, and a control bridle connected to the suspending bridle and the draft bridle, the connection between the control bridle and the draft bridle being through a pair of sheaves for tilting the bucket in carrying position.

The present improvement comprises a means for simplifying the tilting arrangement in the carrying position, including a new location for the tilting sheaves, wherein they are kept away from the material which the bucket is handling and, consequently, are not liable to become clogged with the same.

The invention further comprehends the shortening of the suspending bridle for the purpose of reducing the head-room necessary under the boom in the carrying and dumping positions, and thus a greater amount of material is permissible under a boom at a given position than is possible in the operation of other designs.

Briefly, the bucket comprehends a short suspending bridle with spreader-bar, a draft bridle, and an adjusting bridle running through the sheaves of the spreader-bar to the draft bridle. The adjustable bridle is flexible and as it tends to steady the bucket in hoisting, besides coming into play in co-operation with the draft bridle in crowding or tilting the bucket forward, so that the bucket assumes the correct digging angle, it may properly be called an adjustable control bridle. The spreader-bar is in the form of a large shackle and spans the complete width of the bucket. It is arched in the center to facilitate the removal of the material and at either end is fitted with a knuckle-joint shackle, to which are con-

nected swivel housings for the sheaves, so that the latter can assume any position.

In the drawings

Figure 1 is a plan view of the shovel;

Figure 2 is a side view in digging position;

Figure 3 is a similar view, but in carrying position;

Figure 4 is a side view in dumping position; and

Figure 5 is a sectional detailed view of the spreader-bar taken on the line 5—5 of Figure 2.

In the accompanying drawings I have illustrated the preferred embodiment of my invention, but the construction therein shown is to be understood as illustrative only and not as defining the limits of the invention.

Referring now more in particular to the accompanying drawings, let 5 denote the shovel, which is substantially the same as in the patent above referred to, said shovel being closed at the bottom and rear but open at the front and top. Digging toes or teeth 6 are positioned at the lower front edge of the bottom of the shovel, while the front end of said shovel is provided with draft lugs 7 which extend beyond the front edge of said shovel and extend rearwardly for an appreciable distance along its sides for the purpose of stiffening and lending rigidity to the structure. Positioned above said draft lugs are upstanding ears 8. The numeral 9 designates the spreader-bar, which is arched in the center, as clearly shown in Figure 5, the apex thereof being provided with an aperture 9^a for connection with a fall rope (not shown). The outer ends of said spreader-bar 9 are fitted with swivel housings 10 for the sheaves 11 and in view of the knuckle-joint shackle 12, the said sheaves are enabled to assume different positions, as will presently appear. Said spreader-bar 9 is directly connected to the sides of the shovel through the medium of the suspend-

ing bridle 13, the upper end thereof being shackled to said spreader-bar as indicated at 14, while the other end is loosely or pivotally connected to the respective sides of the shovel, as shown at 15, said points of connection being rearwardly of the center of gravity thereof (see Figure 2). Between the shovel and the haul cable 16 is a draft bridle 17 comprised of two converging members, the rear ends of said members being pivotally connected to the forward ends of the draft lugs 7, while the forward ends of said hauling bridle are pivotally connected to shackle 18 carried by the haul cable 16.

15 As clearly shown in the drawings, I now connect the adjustable control bridle 19 to the ears 8 and pass the same over the sheaves 11, whereupon the two members comprising said bridle converge for connection to the hauling bridle 17 through the medium of the shackles 20.

Figure 2 of the drawings illustrates the shovel in digging position. It will be observed that the adjustable control bridle 19 may be so adjusted on the draft-bridle 17 that the pull exerted by the haul rope 16 will be thrown directly on the upper forward edges of the shovel, which has a tendency to facilitate the digging of the toes 6. 30 When in carrying position, the hauling in of the fall rope elevates the sheaves 11 and, since the draft bridle is no longer operating as a pulling element, the adjustable control bridles are held taut, causing the shovel to 35 assume a tilted position.

The operation of the device is as follows:

The shovel is lowered into contact with the ground by paying out the fall rope. The suspending bridle 13, draft bridle 17, and adjustable control bridle 19 assume the positions shown in Figure 2 during the loading of the shovel. The shovel is then drawn forwardly by the pull exerted on the hauling cable 16 transmitted to the shovel 45 through the draft bridle 17 and the adjustable control bridle 19. The extent of the digging angle assumed by the bucket is directly controlled by the adjustable control bridle 19, the inclination of the shovel being varied so as to regulate the depth of cut by changing its point of connection with the draft bridle through the medium of adjusting shackles 20. When the shovel has been 50 filled, it is hoisted by hauling in the fall line, 55 while keeping a tension upon the haul cable 16, the effect of which is to tilt the forward end of the bucket to prevent spilling of the load, as shown in Figure 3. Obviously it is only necessary to pay out the haul cable 16 60 in order to slacken the adjustable control bridle 19 and cause the shovel to assume the dumping position shown in Figure 4.

What I claim is:

1. In a device of the class described, the combination of a shovel, a suspending bridle

therefor connected to the shovel rearwardly of the center of gravity thereof, a spreader-bar connected to the suspending bridle and provided with sheaves, a draft bridle directly connected to said shovel, and an adjustable control bridle running through the sheaves of said spreader-bar and having one end connected to the shovel and the other to said draft bridle said spreader bar being also arched to clear the load carried by said 75 bucket. 70

2. In a device of the class described, the combination of a shovel, a suspending bridle therefor connected to the shovel rearwardly of the center of gravity thereof, a spreader-bar connected to the suspending bridle and provided with sheaves having swivel housings, a draft bridle directly connected to said shovel, and an adjustable control bridle running through the sheaves of said spreader-bar and having one end connected to the draft bridle. 80

3. In a device of the class described, a shovel, means for suspending it including a spreader-bar, a haul rope, a draft bridle fixedly and directly attached to said shovel and said haul rope and a control-bridge adjustably connected adjacent the forward portion of said draft bridle and having operative connection with said spreader-bar 90 whereby the angle of inclination of said shovel may be varied. 95

4. In a device of the class described, a shovel, means for suspending it including a spreader-bar having sheaves with swivel housings, a haul rope, a draft bridle fixedly and directly attached to the shovel and said haul rope, and a control-bridge passing through the sheaves of said spreader-bar 100 and being adjustable at its forward portion relatively to the corresponding portion of said draft bridle, whereby the angle of inclination of said shovel may be varied. 105

5. In a device of the class described, the combination with a shovel, a haul rope, a suspending bridle connected to said shovel rearwardly of the center of gravity thereof, a spreader-bar connected to said suspending bridle and adapted for direct connection with a fall rope, said spreader-bar having 110 sheaves with swivel housings at its opposite ends, a draft bridle directly connected to said shovel and said haul rope, and a control-bridge adjustably connected to said draft bridle and running freely through the 115 sheaves of said spreader-bar and having one end connected to the upper forward portion of said shovel. 120

6. In a device of the class described, the combination with a shovel, a haul rope, a spreader-bar adapted for direct connection with a fall rope and having swivelled sheaves at its opposite ends, a suspending-bridge connected to said shovel rearwardly of the center of gravity thereof, and com- 125 130

posed of two members each connected to the
ends of said spreader-bar, a draft-bridle
comprising a pair of forwardly converging
members directly connected to said shovel
5 and meeting at and joined to said haul rope,
and a control-bridle comprising two con-
verging members having their forward ends
adjustably connected to said draft-bridle,
the other ends thereof freely passing over
10 said sheaves of said spreader-bar and fixedly
connected to the upper forward portions of
said shovel.
